CANDLEHOLDER

Charles Fischett, South Ozone Park, N.Y.
Application June 3, 1957, Serial No. 46,468

Term of patent 14 years

(Cl. D48—2)

Fig. 1.

Fig. 2.

Fig. 3.

Fig. 1 is a top plan view of a candleholder embodying my new design.

Fig. 2 is a side elevational view thereof.

Fig. 3 is a reduced perspective view thereof with the flower removed for purpose of illustration.

In the drawing the calyx of the flower is shaded in such a manner as to indicate contrasting colors between the inner flower and the calyx.

I claim:

The ornamental design for a candleholder, as shown and described.
